PHASE AND FREQUENCY MODULATION

Murray G. Crosby, Riverhead, N. Y., assignor to
Radio Corporation of America, a corporation of
Delaware

Application October 24, 1936, Serial No. 107,333

9 Claims. (Cl. 250—6)

This invention concerns a method of and means for signalling by transmitting and receiving wave energy modulated in frequency or phase wherein high frequency or phase deviation is accomplished in accordance with the modulating potentials. The subject matter disclosed herein is related to the subject matter disclosed in my United States application #317,617 filed February 7, 1940, said latter application being a division of 10 the present application.

In my system at the transmitter I may use any of the known means for producing high frequency or phase deviations of the wave energy in accordance with signals and for propagating the same either by way of natural mediums or by conductors to a point at which they are to be received and demodulated. A frequency divider is employed at the receiver to reduce the frequency or phase deviation of the received wave 20 so that the devices for converting the phase or frequency modulation into amplitude modulation, operate on a wave whose degree of frequency or phase deviation is reduced with respect to the deviation of the propagated and received wave. This process has special application to phase 25 modulation reception since it enables the reception of wide-band phase modulation on certain types of phase modulation receivers which are normally limited to the reception of phase modulation 30 using a maximum phase deviation of less than 90°.

In the prior art of phase modulation reception on the filtered or synchronized carrier type of receiver, maximum phase deviation has been limited to approximately 90°. Since this type of 35 reception was accomplished by combining a locally synchronized carrier, or carrier from which the signal modulations have been stripped, with the incoming modulated carrier to detect the 40 amplitude changes of the resultant, a phase deviation of 90° would vary the amplitude of the resultant between zero and twice its unmodulated amplitude.

My method of overcoming these limitations as 45 to the phase deviation of phase modulation consists in the application of frequency division at the receiver. This permits the transmission or propagation of wave energy of extremely high phase deviation at signal frequencies. Means for 50 producing a high degree of phase modulation has been shown in my United States application #588,309 filed January 23, 1932, Patent #2,081,577 dated May 25, 1937. As to the means for producing the division at the receiver, it is well known 55 that an oscillator, preferably a multivibrator os-

cillator, may be held in step with an external alternating voltage of a frequency an integral multiple lower than the frequency of the multivibrator, as illustrated by the constants of its circuits. Thus, a 100 kc. multivibrator may be 5 held in synchronism with a 300 kc. voltage. This method of frequency division has properties in common with frequency multiplication in that the phase or frequency deviation of the wave which is frequency divided is divided by the order of frequency division. Hence, a 300 kc. voltage with a phase deviation of 180°, when divided to a 100 kc. voltage, will have a phase deviation of 60°. Thus, the original phase deviation has been reduced to one-third the original deviation. 15 Similarly the 300 kc. voltage with a frequency deviation of 3 kc. when frequency divided to 100 kc., will have a frequency deviation of 1 kc. This can be seen when it is considered that the process of frequency division consists of the holding in 20 step of the harmonic of the multivibrator wave with the fundamental of the wave to be frequency divided. Thus, the third harmonic of the 100 kc. wave from the multivibrator is held in 25 step with the 300 kc. to be divided. Consequently, if the third harmonic of the multivibrator were shifted 3 kc., the fundamental would have to be shifted 1 kc. to remain in harmonic relation. The same is true with respect to phase deviation when the phase deviated wave is divided 30 as to frequencies.

It might be argued that frequency division at the receiver has no advantage since in the division process the carrier has not been raised with respect to the noise coming in on the antenna, 35 or other receiving circuit. However, while the phase modulated wave with the higher phase deviation has not been changed with respect to the incoming signal-to-noise amplitude ratio, the ratio of the phase deviation of the modulated 40 wave to the phase deviation produced by the noise has been changed. That is to say, the signal-to-noise ratio of a wave, the phase deviations from the signal frequency of which is high, is higher than the signal-to-noise ratio of a wave 45 of small phase deviation at signal frequency. Since the receiver receives only phase modulations, the effective phase deviation produced by the combination of the signal and the noise must be considered. Thus, the signal-to-noise ratio at 50 the receiver output depends upon the signal phase deviation to noise phase deviation ratio. For a given signal-to-noise amplitude ratio, the effective phase deviation produced by the noise is constant. Consequently, the higher the phase 55

deviation of the signal wave is made, the higher will be the signal-to-noise ratio at the receiver output terminals. Hence, in applying a high phase deviation at the transmitter, when this phase deviation is reduced to the proper value for detection, the noise is reduced in the same ratio and the signal phase deviation to noise phase deviation ratio remains high. The improvement that may be effected in this manner is therefore proportional to the degree of frequency division applied at the receiver. That is, a frequency division of "N" times would make the signal-noise ratio "N" times as great or would effect a power improvement of "N" squared.

Although the above explanation is specific to phase modulation, it will be understood that due to the similarities of frequency and phase modulation, the words "phase modulation" and "frequency modulation" may be inter-changed. For purposes of convenience the words "wavelength modulation" will be used and when used, will denote modulation in phase or frequency even though phase modulation and frequency modulation, as is well recognized, each have separate and distinct characteristics, as well as characteristics in common. Thus, frequency modulation may be transmitted with a high frequency deviation and frequency division may be applied at the receiver to reduce the frequency deviation of the modulated wave and the frequency deviation of the noise at the same time while preserving the high ratio of their respective frequency deviations. For instance, a frequency deviation of 100 kc. at signal frequency may be applied to the wave energy to be propagated and a frequency division of 10 to 1 may be applied at the receiver to the received wave to reduce the deviation at signal frequency to 10 kc. The selectivity channels preceding the frequency divider may then be 200 kc. wide and those following the divider need be only 20 kc. wide. The sloping filter under these circumstances would be required to convert a 10 kc. frequency deviation at signal frequency into amplitude modulation instead of a 100 kc. frequency deviation.

This type of reception may also take advantage of the inherent limiting properties of a multivibrator wherein its output amplitude is constant even though the input amplitude varies over a rather wide range. Hence, the multivibrator may take the place of the amplitude limiter normally required in a frequency or phase modulation receiver. The use of the multivibrator for a limiter also has the advantage that when the signal fades, the noise does not rise to prohibitively high values as it does in the case of the over-loading type of amplitude limiter and in the automatic volume control type of limiter. This is due to the fact that when the signal fades it merely loses control of the multivibrator whereas with the overloading type of limiter and automatic volume control type of limiter, when the signal fades the noise is amplified to extremely high values.

In describing specific embodiments of my invention reference will be made to the attached drawings wherein;

Figure 1 illustrates diagrammatically the essential elements of a receiver arranged in accordance with my invention. The various receiver units have been shown as rectangles since the circuits per se of some of the units form no part of the present invention;

Figure 2 illustrates the details of a multivibrator

suitable for use as one of the units of the receiver of Figure 1;

Figure 3 illustrates a wide band phase modulator;

Figure 4 illustrates a wide band frequency 5 modulator. Here again, as in Figure 1, units of the transmitter are shown as rectangles since the details of the said unit per se form no part of the present invention;

Figure 5 illustrates a modification of the receiver of Figure 1;

Figure 6 illustrates a modification of the circuits of Figures 1 and 5. Figure 6 shows how to increase the amount of division possible. The divided wave energy is heterodyned to a higher 15 frequency and again divided.

Figure 1 illustrates by block diagram, how frequency division may be applied to a phase or frequency modulation receiver. The signal to be demodulated is fed from the antenna to a radio 20 frequency amplifier 1 where it is amplified. The amplified signal is then fed to a first detector and high frequency oscillator into which it is beat down to an intermediate frequency and amplified if desired. The intermediate frequency energy 25 is then impressed on band pass intermediate frequency amplifier 3, which amplifies and selects the intermediate frequency energy. 4 is a frequency divider which, as stated, may be a multivibrator and has its input connected to the output 30 of the intermediate frequency amplifier 3. The unit in 4 may take the form of an unstable oscillator which is unstable enough to follow the frequency or phase deviations of the modulated wave, or it may take the form of a multivibrator 35 as shown in Figure 2 which will be described in detail later. The output of 4, e. g., the divided wave energy, is impressed on the input of a unit 5 which contains any form of frequency modulation or phase modulation receiver known in the 40 art. If frequency modulated waves are being received, the unit 5 may employ principles of receiving frequency modulation such as described in

55

In general, the unit 5 may contain a limiter, sloping filter, and detector. The limiter may be eliminated if sufficient limiting is obtained inherently in the multivibrator in the unit 4. If phase modulation is being received, unit 5 may 60 employ principles of receiving phase modulation as are described in

Patent #2,085,008 dated June 29, 1937. 75

If, for instance, the principles of demodulation disclosed in my United States application #47,933 filed November 2, 1935, Patent #2,085,008 dated June 29, 1937 are applied, the frequency divided energy is fed through an unneutralized crystal filter and detected. If automatic frequency control is applied, the audio frequency energy obtained from the output of 5 may be used to control the frequency of the high frequency oscillator 10 in unit 2. The audio frequency control energy derived from the output of 5 may also be applied to control the frequency of a second oscillator of a triple detection superheterodyne receiver.

The multivibrator of Figure 2 is of the negative transconductance pentode type. The values of resistance R and condenser C determine the time constants of the circuit and consequently the frequency at which the multivibrator oscillates. R_1 is a grid leak and C_1 is a bypass condenser. The energy to be frequency divided is fed to the grid of the pentode 8 by way of transformer 7. The divided energy is taken from the plate circuit of the pentode by way of transformer 9.

This type of multivibrator which is of the negative transconductance type will now be described. Briefly, the oscillations take place by virtue of the negative resistance characteristic existing between the suppressor grid 12 and screen grid 14 of the tube 8 when proper element voltages are applied. With a resistance, R, in the screen-grid circuit and a condenser, C, coupling the screen grid to the suppressor, approximately square wave form oscillations will take place at a frequency depending upon the time constant of the combination of resistors R and R_1 and the capacity C. Due to the fact that these oscillations are quite unstable as to frequency, an alternating voltage fed to the control grid 16 of the tube, for instance by means of transformer 7 of Figure 2, will cause the oscillations to lock in step with the applied alternating voltage at a frequency which is an integral multiple or sub-multiple of the applied alternating voltage frequency. By using the sub-multiple lock-in, frequency division is obtained. The frequency divided energy may be taken directly from the resistor and condenser circuits R, R_1 and C, but may be conveniently taken from the plate circuit by taking advantage of electron coupling. Since the electron stream within the tube may be modulated by the oscillations of the multivibrator circuit, the plate current will vary in accordance with these oscillations. Consequently, the output may be taken from the plate circuit by inserting an output circuit such as the transformer 9 in Figure 2. It will be noted that since the anode is coupled to the other electrodes in the tube and in particular, the auxiliary electrodes in the circuit RC, by way of the electron stream only of the tube, changes in load cannot affect the input and auxiliary electrodes or the circuits connected therewith.

The primary and/or secondary winding of transformer 7 may be tuned to a frequency f e.g., the frequency of the wide band phase or frequency modulated energy to be demodulated. The primary and/or secondary winding of the transformer 9 may be tuned to a frequency

$$\frac{f}{N}$$

where N equals the number of times it is desired to reduce the incoming frequency. The multivibrator of Figure 2 is included in the unit 4 as

shown by the dotted lines enclosing said unit and enclosing Figure 2. The incoming wave energy excites the control grid of 8 and locks in step the oscillations which are produced therein of a frequency determined by R and C. By adjusting 5 R and C to the proper values the desired order of frequency division may be obtained. The signal carrying energy of reduced frequency appears in 10 9 and is impressed on 5. This type of pentode 15 negative trans-conductance multivibrator is particularly suited for such operation since the control grid is available to apply the energy and the electron coupled output may be taken from the plate circuit. However, any other type of multivibrator may serve the purpose equally well. 15

The process of frequency reduction employed in this receiver is not limited to the use of a single frequency dividing oscillator. I contemplate the use of several multivibrators, cascaded so that each one performs a part of the frequency dividing. Such a system has been illustrated in Figure 5 wherein the rectangles 4 and 4' designate two frequency dividing units in cascade. For instance, if a 600 kc. intermediate frequency wave 20 is to be divided to 100 kcs., the 600 kc. energy 25 may be fed to the first frequency dividing oscillator in 4 where it will be divided by a ratio of 3 to 1 or to 200 kc. This 200 kc. energy may then be fed to the frequency dividing oscillator in 4', 30 which may apply a frequency division of 2 to 1 so as to divide the frequency to 100 kc. Such multi-stage dividing has the advantage of greater stability since the lower ratios of frequency division hold "in step" more easily. Amplification may 35 also be applied between limiting stages to further improve the stability. An amplifier has been shown connected between the stages 4 and 4' of Figure 5.

For high ratios of frequency division the process of frequency division and heterodyning may be combined. Thus, in the instance of the frequency division of the 600 kc. intermediate frequency energy, if a greater frequency division ratio than 6 to 1 were desired with a final frequency of 100 kc., a frequency division of 3 to 1 may be first applied to divide the frequency to 200 kc. This 200 kc. energy may then be heterodyned to, for instance, 1000 kc. The 1000 kc. energy may then be applied to another frequency dividing 45 system to obtain a frequency division from 1000 to 100 kc. A total frequency division of 30 to 1 is, in this manner obtained in the whole process of division and heterodyning. By further heterodyning and division the process of frequency division may be carried to any degree desired. As 50 has been described in various copending applications, the process of heterodyning phase or frequency modulated waves does not alter the degree of phase or frequency modulation of the 55 wave whereas the process of dividing the phase or frequency modulated wave also divides the phase or frequency modulations of the wave. A receiver including the heterodyning means described above has been illustrated in Figure 6 of 65 the drawings.

In Figures 3 and 4 I have shown diagrammatically a wide band phase modulation transmitter and a wide band frequency modulation transmitter respectively. These modulations may be 70 of any type known in the art. For example, I may use the wide band phase modulation of Crosby United States application #588,309 filed January 23, 1932, Patent # 2,081,577 dated May 25, 1937, or the wide band frequency modulation 75

of United States application #13,886 filed March 30, 1935.

I claim:

1. The method of improving signalling by increasing the signal-to-noise ratio in phase modulated wave energy used in signalling which includes the steps of, modulating the phase of said wave energy through a wide range or degree at signal frequency whereby the ratio of signal modulation to noise modulation of said wave energy is high, transmitting said wave energy so modulated to the point of reception, producing oscillations with phase variations characteristic of the phase modulations on said wave energy at said point of reception, passing said produced oscillations over a single path only to demodulating means and dividing the frequency of the said oscillations and simultaneously reducing the amount of phase variations thereof in said single path.
2. A method as recited in claim 1 including the additional step of, dividing the frequency and simultaneously reducing the phase variation of the oscillations, of divided frequency and reduced phase variation, in said single path.
3. A method as recited in claim 1 wherein the said oscillations are limited in amplitude as they are being divided as to frequency in said single path.
4. A method as recited in claim 1 wherein said oscillations are limited in amplitude in said single path.
5. The method of demodulating wave energy

the length of which has been modulated through a wide range or degree before transmission to improve the signal-to-noise ratio in the energy resulting from demodulation thereof which includes the steps of, producing voltages characteristic of the wave energy so modulated in length, passing said voltages over a single path only to wave demodulating means and dividing the frequency of the voltages passed over said single path to reduce the range or degree of modulation thereof. 10

6. A method as recited in claim 5 wherein the voltages are limited in amplitude in said single path.

7. A method as recited in claim 5 wherein said voltages are limited in amplitude while being divided as to frequency in said single path. 15

8. In a system for demodulating transmitted wave energy the length of which has been modulated through a wide range or degree to obtain a favorable signal-to-noise ratio in the wave energy so transmitted, means for picking up said wave energy and producing voltages characteristic of the said wave energy so modulated, wave length demodulating means, a single path only coupling said demodulating means to said voltage producing means and a frequency divider in said single path. 20

9. A system as recited in claim 8 wherein amplitude limiting means is included in said single path to limit the amplitude of the voltages passed thereby. 30

MURRAY G. CROSBY.
